HEAD LAMP

Thomas G. Melish, Cincinnati, Ohio

Application December 18, 1933, Serial No. 702,842

2 Claims. (Cl. 240—44.25)

This invention relates to improvements in head-lights, particularly for automobiles, in which the light is a double filament lamp bulb having its filaments relatively disposed one above another and in relation to the focal axis of the reflector of the headlamp, and upon independently energizing the filaments, different angular directions of light beam reflection is obtained as upward or downward.

10 The object of this invention is to provide inexpensive means to move the lamp bulb horizontally sidewise so as to throw the light beam toward one side of the road away from the eyes of the driver of an approaching automobile, the lamp bulb movement resulting in diverting the light beam from either of the specific directions obtained by 15 separately energizing the filaments in the normal position of the lamp bulb within the reflector to a direction at an angle thereto as from either up and down to right or left, depending upon the horizontal direction the bulb is moved from its 20 normal position within the reflector.

In the present instance, with the use of the two filament lamp bulb, the filaments positioned one 25 above the other, up or down light beam reflection is controlled by energizing one or the other of the filaments. The upper filament obviously with the usual type of reflector will throw the beam down on the road near the car, while the lower 30 filament when energized will throw the beam up and at a greater distance. This so-called driving beam which throws the light for a long distance ahead ordinarily blinds the approaching driver. The object of this invention is to divert the driving beam to the right-hand side of the road out 35 of the eyes of approaching motorists by shifting the lamp bulb sidewise temporarily without de-energizing the filament until the approaching car has passed.

40 Various other features and advantages of the invention will be more fully set forth in the description of the accompanying drawings, in which:

Figure 1 is a horizontal section through the 45 rear portion of an automobile headlamp casing and reflector, showing a lamp holding fixture for swinging the lamp bulb horizontally sidewise with the fulcrum in rear of the lamp bulb socket and fixed to the inner side of the outer casing.

50 Figure 2 is a front elevation of the same.

Figure 3 is a section on line 3—3, Figure 1.

Figure 4 is a vertical section through the rear portion of a headlamp casing and reflector of a modified form of lamp bulb holding fixture with 55 the fulcrum located above the lamp socket and

the fixture mounted as in the form shown in Figure 1 upon the inner side of the outer casing.

Figure 5 is a section on line 5—5, Figure 4.

Figure 6 is a section on line 6—6, Figure 5.

Figure 7 is a perspective view of a modified form 5 of fixture of the types shown in Figures 4 to 6 inclusive.

Figure 8 is a central horizontal section through the rear portion of a headlamp casing and reflector disclosing another modified form of lamp 10 bulb fixture as applied to the rear side of the reflector.

Figure 9 is a front elevation thereof.

I am familiar with the fact that various methods are employed by manufacturers of automobile headlight lamps to effect a so-called "passing beam."

One method employed is to equip the lamps with three filament bulbs, two filaments being positioned one above the other, and the third off to 20 one side. The upper and lower filaments are used to direct the light either near the motor car, or up on the road at a distance from the car, and the third filament is used to direct the light to the 25 side of the road, away from the eyes of the approaching motorist.

This method of directing the light beam to one side has the following disadvantages. For a short interval of time, as the light is switched from one filament to another, the road is dark. The present invention contemplates reducing the expense 30 of effecting a "passing beam" by the use of the ordinary small two filament bulb and an inexpensive mechanism to swing it sidewise.

The structures of the outer casing and reflector 35 differ from one another in headlamps used for various makes and grades of automobiles. Therefore, slight modifications in the light bulb holding fixtures are required to make the same readily available for use in the present various types of 40 headlamps. In each case however the movement of the two filament light bulb is substantially horizontal and the results are the same.

Referring to the drawings, 1 indicates the rear portion of an automobile headlamp casing and 45 the rear portion of a reflector mounted within the casing and in spaced relation thereto. The general construction of headlamp not forming a part of the present invention, no detailed disclosure thereof is made herein, and it may follow any of 50 the commercial designs now used with a reflector preferably of parabolic type.

3 indicates the commercial double filament electric light bulb removably engaged into the forward end of a double end bayonet type of socket 55

4. The socket is positioned to mount the light bulb with its filaments one above the other at relatively opposite sides of a horizontal line through the focal axis of the reflector. A circuit lead connector plug 5 is engaged into the rear end of the socket 4 for making the necessary circuit connections with the lamp bulb filaments through the socket in the well-known manner.

In the form of light bulb socket fixture shown 10 in Figures 1 to 3 inclusive, the socket 4 is longitudinally slidably mounted within the forward end of a hinged arm 6, pivotally mounted upon a bracket 7 fixed to the inside of a headlamp outer casing 1. The socket at its upper side is provided 15 with a laterally vertically extended lug 8 engaged by a set-screw 9 connecting with the hinged arm 6 for making the required focal adjustment of the light bulb.

The bracket 7 is of prong configuration providing 20 a pair of oppositely disposed arms 7a—7a, one carrying an electro-magnet 10 for attracting or swinging the arm to one side from its central or normal focal position of the light bulb to offset the same from the focal axis of the reflector for 25 diverting the light beam from either up or down direction obtained by selectively energizing either of the filaments to a sidewise direction without deenergizing the filament in service.

A spring 11 having one end fixed to the socket 30 carrying arm 6 of the light bulb holding fixture has its opposite end fixed to one end of a screw 12 engaged through an arm 7a of the bracket 7, the spring serving to swing the arm to its normal position against a stop screw 13 carried by the arm 7a of the fixture when the magnet 10 is deenergized.

The modified form of fixture shown in Figures 4 to 6 inclusive in detail is substantially the same as the type of fixtures shown in Figures 1 to 3 inclusive excepting that the fixture is mounted 40 upon the inside of the outer casing 1 in a vertical position instead of horizontally, bringing the fulcrum of the swinging arm 6 vertically above the socket 4.

In Figure 7 the light bulb socket holding fixture 45 is composed of sheet metal stampings comprising a cradle 14 having a pair of spaced parallel limbs 15—15 apertured to receive the light bulb socket 4. The limbs at their upper ends are pivotally mounted upon the lateral extension 16 of a bracket 50 17. The bracket is adapted to be rigidly fixed by any well-known means upon the rear side of the headlamp reflector. The bracket is provided with a pair of spaced parallel limbs 18—18, one for supporting an electro-magnet 10 cooperating with a limb 19 of the cradle 14, and the second limb 18 of the bracket carrying a stop screw 20 engaging with a second limb 19 of the cradle and also providing a connection for a spring 21 connecting with the cradle for normalizing the cradle when 55 the magnet is deenergized.

In the modified forms shown in Figures 8 to 11 inclusive, the fixture provides a sheet metal bracket 17 somewhat similar to the bracket shown in Figure 7 except that in the latter instance the light bulb socket 4 is directly mounted upon the bracket engaged between and pivoted to a pair of ears or limbs 22—22, laterally extending respectively from the opposite edges of the base and centrally thereof.

In Figure 10 the normalizing spring 21 is housed or socketed within the bore in the core of the magnet 10 engages directly against the socket 4.

In Figure 11 the socket 4 at its rear end has a collar 23 fixed thereon providing an armature cooperating with the magnet 10. The electro-magnet 10 provides a means for swinging the socket under remote control as for instance, by operating a push button electric circuit closing switch either by the hand or foot of the operator, to temporarily shift the bulb and its socket to one side of its normal position as long as the circuit is held closed by the operator.

In the normal operation of the headlamp, the light bulb and its socket are stationed in a proper focal location with respect to the reflector. The electric circuit for the filaments is remotely controlled as through a switch mounted upon the 15 dash or control board of the automobile. Thus, upon energizing the upper filament of the light bulb, a light beam is reflected in an angular direction downwardly and when the lower filament is energized the beam will be directed upwardly. 20

Whenever occasion requires, the light beam can be diverted from either its up or down direction by energizing the electro-magnet 10 which when energized will instantly swing the light socket and bulb to one side, resulting in a diversion of 25 the light beam sidewise as toward the right-hand side of the roadway without any break in the light.

Having described my invention, I claim:

1. In an automobile headlamp, a casing, a reflector within the casing, an electric light bulb holding fixture mounted in rear of the reflector movably sustaining a lamp bulb socket passing through an opening in the vertex of the reflector, the socket carrying a light bulb equipped with 35 two filaments positioned one above the other and at relatively opposite sides of the focal axis of the reflector, said fixture constituting a bracket having a base and a pair of oppositely disposed arms laterally extending from the base, a third 40 arm pivoted between said arms to the base and carrying said lamp socket, an electro-magnet carried by one of said first mentioned arms and when energized cooperating with said third arm for 45 swinging the same in a lateral offset relation to the focal axis of the reflector, a stop screw on the second arm of said bracket for limiting the swing of said third arm, and a spring connecting with 50 said third arm and said second arm for yieldingly urging said third arm against said stop screw and normally maintaining the socket and lamp bulb at the focal axis of the reflector.

2. In an automobile headlamp, a casing, a reflector within the casing, a bracket mounted in rear of the reflector, a lamp bulb socket pivotally mounted on said bracket and passing through an opening in the vertex of the reflector, the socket carrying a light bulb equipped with two filaments positioned one above the other at relatively opposite sides of the focal axis of the reflector, an electro-magnet mounted on said bracket at one side of the socket and when energized cooperating with the socket to swing the socket in a lateral offset relation to the focal axis of the reflector, a stop screw on said bracket at 65 a side of the socket opposite said electro-magnet for limiting the retreating swing of the socket, and a spring for yieldingly urging said socket against said stop screw normally maintaining the socket and its light bulb coaxially with the focal axis of the reflector.

THOMAS G. MELISH.
